[57] CLAIM

The ornamental design for a multi-unit belt display fixture, substantially as shown.

DESCRIPTION

FIG. 1 is a perspective view of a multi-unit belt display fixture showing our new design;

FIG. 2 is a front elevational view thereof, the rear being identical;

FIG. 3 is a side elevational view taken from the left of FIG. 1, the side opposite being identical;

FIG. 4 is a top plan view thereof; and

FIG. 5 is a bottom plan view thereof.
